UNITED STATES PATENT OFFICE.

ALEXANDER GORDON, OF DETROIT, MICHIGAN.

APPARATUS FOR CURING TOBACCO.

SPECIFICATION forming part of Letters Patent No. 234,467, dated November 16, 1880.

Application filed August 30, 1880. (No model.)

To all whom it may concern:

Be it known that I, ALEXANDER GORDON, of Detroit, Wayne county, Michigan, have invented an Improvement on Tobacco-Sweaters, 5 of which the following is a specification.

The nature of this invention relates to new and useful improvements in apparatus for curing tobacco; and the invention consists in the peculiar construction, arrangement, and 10 operation of the several parts, as more fully hereinafter described.

Figure 1 is a perspective view with the doors opened. Fig. 2 is a vertical cross-section.

In the accompanying drawings, which form 15 a part of this specification, A represents a box or room lined with sheet metal, (galvanized iron being preferred,) and provided with doors B, which should be fitted as near steam-tight as possible. D is another box made of per- 20 forated boards and externally covered with sheet metal. This box is also provided with doors E, also made of perforated boards and covered with sheet metal, and is placed within the outer box, A, so as to leave a steam- 25 space, F, between the two. The door C in the box A, lined with sheet metal, covers a case which leads through the wall of the box D, and a steam-pipe, H, leading from any source 30 of supply will discharge steam into the space F between the boxes A and D, the latter of which may, if desired, be placed upon a truck. I represents another box, smaller than the box D, and is designed to contain the tobacco to be sweated. This box is provided with a door, 35 J, through which the interior thereof may be reached, and the box is placed upon a truck, K, to facilitate its removal from the box D. A steam-pipe, L, with a suitable valve, M, admits steam from any suitable source of sup- 40 ply to the space between the boxes I D.

It will be perceived that by constructing the box D of perforated boards externally covered with sheet metal the latter will be quickly heated by the inflowing steam and 45 the heat imparted to the sheet metal will be radiated through the perforations in the boards into the space between the boxes D and I, thereby heating the latter. The external sheet-metal covering of the perforated box is also 50 stiffened and strengthened by the boards, the perforations in which allow the heat to pass

freely through them, and at the same time the construction is cheaper, and capable of operating with less heat than a metallic box made sufficiently thick to be operative.

55

It will also be observed that by constructing the outer box, A, of wood lined with sheet metal the latter will be quickly heated by the inflowing steam through the pipe H, and that the wood of the box A being a poor conductor 60 of heat, the heat from the lining will be radiated inwardly upon the exterior lining of the box D, thereby more quickly heating the latter.

In practice the tobacco to be sweated is placed in the box I, which is run into the box 65 D. The doors of the boxes A D are then closed and steam admitted through the pipe H into the space F, and the heat therefrom radiates through the walls of the box D, the boards of which it is constructed being perforated to facilitate such radiation. During the treatment the door C may be opened and a thermometer inserted to determine the heat in the interior, or the hand to determine the moisture. Should the air be too dry, the valve M may be opened 70 and a greater or lesser quantity of steam may be admitted into the box D, and the moisture therefrom will be communicated through the walls of the box I to the tobacco inclosed therein.

80

By this construction I am enabled to more thoroughly and evenly cure tobacco than can be done by the devices for the purpose already in use, and to toughen the leaf and make it stronger.

85

What I claim as my invention is—

1. In a tobacco-curing apparatus, the intermediate box, D, made of perforated boards and externally covered on all its sides with sheet metal, substantially as described, and 90 for the purpose set forth.

2. A tobacco-curing apparatus provided with the outer box, A, lined with sheet metal, and the intermediate box, D, made of perforated boards and externally covered on all 95 its sides with sheet metal, with a space between the boxes, substantially as described, and for the purpose set forth.

ALEXANDER GORDON.
